(57) **CLAIM**

The ornamental design for a “holder for a disc-shaped data carrier”, as shown and described.

DESCRIPTION

FIG. 1 is a top plan view of a holder for a disc-shaped data carrier showing our new design;

FIG. 2 is a bottom plan view thereof;

FIG. 3 is a left side elevational view thereof;

FIG. 4 is a top perspective view thereof;

FIG. 5 is a bottom perspective view thereof; and,

FIG. 6 is a cross sectional view thereof, taken on line 6—6 of FIG. 1.
